UNITED STATES PATENT OFFICE.

SEYED KHALIL, OF NEWARK, NEW JERSEY.

COIN OR CHANGE HOLDING AND DELIVERING DEVICE.

Application filed June 30, 1922. Serial No. 571,932.

To all whom it may concern:

Be it known that I, SEYED KHALIL, a subject of the Shah of Persia, and a resident of Newark, in the county of Essex and State of New Jersey, have invented certain new and useful Improvements in Coin or Change Holding and Delivering Devices, of which the following is a specification.

The invention pertains to coin-holding and delivery devices of the character worn by conductors on street cars, and by other persons, for use in making change, and the invention consists in the novel features, structure, and combinations and arrangements of parts hereinafter described, and particularly pointed out in the claims.

One object of the invention is to provide a durable, efficient, improved and simplified construction of coin-holding and delivering mechanism.

A special object of the invention is to provide a mechanism or device of the character described whose parts are, in the main, accurately produced by dies and assembled without the use of solder or rivets and which parts are capable of being wholly or in part disassembled without difficulty so as to render it entirely convenient to apply a repair or new part for a part which might have become impaired through accident or otherwise. It is a special feature of my construction that an unskilled person may remove a damaged part therefrom and substitute a new part therefor without the use of special tools, this feature of my invention avoiding many of the inconveniences as well as much of the expense incident to the repair of coin-holding and delivering devices at present in use.

My invention involves a new construction and arrangement of the coin-delivery or ejecting devices, with the view of securing therein convenience and ease of operation and durability and a disposition thereof in which the parts are not liable to become damaged in use.

The mechanism of my invention comprises a novel sheet metal frame for holding the coin-tubes, novel means for securing the tubes in place and novel coin-delivery devices to be manually operated by a conductor in making change, the whole resulting in the production of a very durable and efficient device possessing many advantages.

The invention will be fully understood from the detailed description hereinafter presented, reference being had to the accompanying drawings, in which:

Fig. 1 is a top view of a coin-holding and delivering device embodying my invention;

Fig. 2 is a rear elevation of the same, with the hinged back or door shown as having been opened, said back being partly broken away;

Fig. 3 is a detached perspective view of one of the manually operative key-frames employed for actuating the coin-delivery rings;

Fig. 4 is a detached perspective view of one of the coin-delivery rings;

Fig. 5 is a detached perspective view of a single-tooth pinion to be actuated by a portion of the key frame shown in Fig. 3 and which has a downwardly extending member to engage an arm of the coin-delivery ring shown in Fig. 4 for imparting oscillatory movement to said ring, and in Fig. 5 is shown a washer through which said downwardly extending member is inserted in the assembly of the parts of the machine;

Fig. 6 is a horizontal section through the entire device taken on the dotted line 6—6 of Fig. 2, the hinged back or door being shown in closed position;

Fig. 7 is a bottom view of the device;

Fig. 8 is a horizontal section through a lower fragmentary part of the device taken on the dotted line 8—8 of Fig. 15, and showing the coin-delivery ring in normal position;

Fig. 9 is a like view of the same showing the coin-delivery ring in the position to which it is moved when the ring is actuated by the key-frame shown in Fig. 3 and the single-tooth pinion shown in Fig. 5;

Fig. 10 is a horizontal section through the device taken on the dotted line 10—10 of Fig. 2;

Fig. 11 is a like section through the same taken on the dotted line 11—11 of Fig. 2;

Fig. 12 is a detached perspective view of the coin-tube base-plate;

Fig. 13 is a detached perspective view of the bottom plate of the device;

Fig. 14 is a vertical transverse section through the device taken on the dotted line 14—14 of Fig. 2;

Fig. 15 is a vertical transverse section through a lower end portion of the device taken on the dotted line 15—15 of Fig. 6;

Fig. 16 is a corresponding section taken on the dotted line 16—16 of Fig. 6;

Fig. 17 is a detached perspective view of one of the vertical end plates of the device, and

Fig. 18 is a detached perspective view of one of the coin-holding tubes.

In the drawings 20 designates the vertical coin holding tubes varying in diameter in accordance with the denominations of the coins to be placed in them, as usual, 21 the coin-tube base-plate to which the lower ends of the tubes are connected, 22 the top or cover plate extending over and engaging the upper ends of said tubes, 23 a bottom plate spaced below said base plate 21 and supporting on its upper face the coin-delivery rings, 24 vertical end plates and 25 a hinged back or door.

The base-plate 21 is separately shown in Fig. 12 and is in one integral piece of sheet metal and formed with openings 26 for the lower ends of the tubes 20 and around said openings with upwardly pressed annular flanges 27 having at their upper edges inwardly turned flanges 28 containing equally spaced apart edge recesses 29.

The base-plate 21 is formed at its ends with up-turned flanges 30 having at their rear edges vertical sleeves 31 and with downwardly and inwardly turned hook-like flanges 32 which extend below and aid in supporting and positioning the bottom plate 23 (Fig. 7). The plate 21 is also formed with a front downwardly extending flange 33 which has inturned flanges 34 extending below and aiding in the support of the bottom plate 23 (Figs. 7 and 14). The plate 21 has slit therefrom and turned upwardly the vertical corresponding standards 34 whose formation leaves holes 35 in the plate, and from these holes narrow recesses 36 extend forwardly; a similar narrow recess 36 is also provided outside of the holes 35 (Figs. 10, 12). At its rear edge the plate 21 is formed with the incut recesses 37. In its rear portion and about in line with the standards 34, the plate 21 is formed with four properly spaced-apart holes 38, whose purpose will be explained hereinafter. The flanges 30 and standards 34 of the plate 21 extend along a curved line corresponding with the general curved shape of the rear edge of the plate and face one another in series, and the upper ends of these flanges and standards are formed with holes 39 which receive a pivot rod 40 whose ends are within the holes in the flanges 30 and do not require to be riveted therein since the rod is held against endwise movement by other features of the structure, as will be explained hereinafter.

The tubes or cylinders 20 are formed from initially flat blanks of sheet metal and are each in one piece of material bent into tubular form, the material being cut out at opposite edges to leave sight-openings or slots 41 in the front of the tubes (Figs. 14, 18). The lower ends of the tubes 20 interlock, after the manner of bayonet joints, with the flanges 28 of the plate 21, and to this end each tube 20 is near its lower end formed with two annular parallel rows of spaced-apart outwardly pressed lugs 42, 43, respectively, the lugs 42 being offset from the vertical planes of and smaller than the lugs 43 and adapted to be inserted downwardly through the recesses 29 in the flange 28 and until the lugs 43 become arrested on the top of said flange, whereupon by giving the tube a partial turn the lugs 42 are carried from the line of the said recesses 29 and below solid portions of the flange 28, the tube thereby becoming locked in position and supported by the lugs 43 and flange 28 over an opening 26 in the plate 21; a reverse operation will permit the withdrawal of the tube from the plate 21. When the tubes 20 are secured to the flanges 28 of the plate 21 the lugs 43, being longer than the lugs 42, cover over and conceal the recesses 29 in said flanges.

The upper ends of the tubes 20 are held stationary by the top plate 22 which is formed with upwardly recessed caps 44 fitting upon the upper ends of the tubes and provided with openings 45 through which coins are introduced into said tubes. The top plate 22 is formed along its front edge with a hollow beading 46 which overhangs and protects the upper ends of the tubes 20 and also receives outwardly pressed lugs 47 formed on the upper front portions of said tubes, the lower flange of said beading closely engaging the lower edges of said lugs 47 and cooperating therewith in holding the front portion of the plate 22 down on the tubes.

The bottom plate 23 matches the general outline of the tube base-plate 21 and is spaced sufficiently below the same to provide a shallow chamber for the oscillatory coin delivery rings 48 which are mounted on said plate 23. The plate 23 is separately shown in Fig. 13, and said plate is formed with coin-discharge openings 49 and also with a series of upwardly pressed bushings 50 which when the parts are assembled engage the lower surface of the base-plate 21 and accurately space the plates 21, 23 apart to form said chamber for the rings 48. The bottom-plate 23 is formed with a series of four holes 51 in vertical alignment with the four holes 38 in the base-plate 21, and also with four slots 52 which are in vertical alignment with the four slots or recesses 36 in said base-plate 21. The holes 51 have

at their edges downwardly pressed flanges or bushings 53 (Figs. 7 and 16) which afford substantial bearings for the lower ends of the stems 54 of the one-tooth pinions 55, 5 and the slots 52 have the metal of the plate at their opposite edges pressed downwardly to form side flanges 56, (Figs. 7, 11 and 15) for the lower ends of the legs 57 of the manually operative key-frames 58, which 10 legs 57 extend downwardly through said slots or recesses 36 in the plate 21 and through said slots 52 in the plate 23 and in operation have an oscillatory movement therein and are guided thereby, the forward ends of the slots or recesses 36 forming stops to limit the movement of said legs 57 and consequently the key-frames 58 and their parts in a forward direction.

The bottom plate 23 is formed at its rear edge with four rearwardly projecting lugs 59 which are wider at their outer than at their inner ends and in the assembled mechanism are directly below the recesses 37 in the base-plate 21. The lugs 59 detachably 25 receive the lower ends of the coiled springs 60 which extend through the said recesses 37 and are detachably caught at their upper ends on lugs 61 formed on the aforesaid key-frames 58. The springs 60 are vertically disposed and are under tension and normally act to pull downwardly on the rear ends of the frames 58 and tilt the legs 57 thereof forwardly against the forward ends of the recesses or slots 36 (Figs. 8 and 11) 30 which ends serve as stops, as aforesaid, to arrest the legs 57 and frames 58 in normal position.

The bottom plate 23 is formed at its two rear corners with holes 62 (Fig. 13) which 40 in the final assembly of the parts of the mechanism are below and in vertical line with the sleeves 31 on the plate 21; bolts 63 pass through the holes 62 and sleeves 31, as hereinafter explained.

Upon the bottom plate 23 are, in the present instance, there being four coin-tubes 45 present, four oscillatory coin-delivery rings 48, all being alike except as to proportions and one being provided for each tube 20. One of the rings 48 is shown separately in Fig. 4. Each ring 48 has a lip 64 and a shank-arm 65 in whose outer end is a polygonal slot or hole 66 and upon whose upper side is a pressed up boss or rib 67. 50 The rings 48 vary in thickness in accordance with the thickness of the coins they are intended to handle and the bosses or ribs 67 will vary in height from the arms 65 in accordance with the thickness of the rings 55 so that the upper edges of all said bosses or ribs may be on the same horizontal plane and freely engage the lower surface 55 of the base-plate 21, the bosses or ribs 67 thus cooperating with the plate 21 to keep

the rings 48 flatwise upon the plate 23. 65 Each ring 48 and all its parts is in one integral piece of sheet metal. The polygonal slots or holes 66 in the arms 65 of the rings 48 receive the lower polygonal ends of the stems 54 of the one-tooth pinion 55 (Fig. 16) and the rings 48 receive their movements from said stems and pinions, said stems and pinions being turned in one direction by the manual action of the operator when coins are to be delivered, as hereinafter explained, and in the reverse direction to restore the rings to normal position, by the springs 60. The stems 54 have polygonal lower ends to snugly fill the polygonal slots 66 in the ring-arms 65, and below said arms said ends of the stems enter and find a substantial bearing in the flanged holes 51 of the bottom plate 23 (Figs. 7 and 16). Above the ring-arms 65 the stems 54 have round hub-portions 68 (Fig. 16) which lie within the bearing holes 38 in the base-plate 21 and within holes in the washers 69 which rest upon the top of said plate 21 and are below the horizontal pinion members 55 from whose inner ends said stems 54 project downwardly. The pinion members 55 serve as cranks from which the stems 54 are turned and which cause the stems to impart the proper oscillatory movements to the coin delivery rings 48. 85

The pinion members 55 are elongated and each is formed on its upper surface with a rib whose cross-section is that of the tooth of a pinion, and hence the member 55 is designated by me as a one-tooth pinion. The pinion member 55 receives its oscillatory movement from the key-frame 58, which is in one piece of sheet metal and of box-like formation and has at its rear edge the spring-lug 61 and at its forward edge a forwardly projecting lever arm 70 whose forward end has a finger or thumb-piece 71. At one side edge the metal of the key-frame 58 is bent downwardly and cut to form a slot 72 and the aforesaid leg 57, and at its other side edge is bent downwardly and cut to form the slot 73 and legs 74 whose lower inner edges straddle and engage the tooth of the pinion 55 (Figs. 8, 9, 10, 16) 100 and serve as gear teeth cooperating therewith. The key-frames 58 are pivotally mounted upon the rod 40, the slots 72 and 73 of said frames being slipped downwardly upon said rod and said frames at the upper ends of said slots being pivotally supported by said rod, and said frames are so positioned on the rod 40 that their legs 57 extend downwardly through the slots 36, 52, respectively, of the base plate 21 and bottom plate 23, that their legs 74 straddle the tooth of the pinions 55 and that their lever arms 70 extend forwardly at the sides of the tubes 20. After the frames 58 have 105

110

115

120

125

been positioned on the rod 40 the coiled springs 60 are applied to the lugs 59 of the bottom plate 23 and the lugs 61 of said frames 58, and these springs being then 5 under tension act to press the legs 57 of the frames 58 against their stops at the forward ends of the recesses or stops 36 in the plate 21. At this time should a thumb-piece 71 of a frame 58 be pressed downwardly, the 10 frame will tilt forwardly in opposition to the stress of the spring 60 and the legs 57, 74 will be swung rearwardly, the leg 57 leaving its stop at the end of the slot 36, as shown in Fig. 9, and the legs 74 acting 15 against the pinion 55 to turn its stem 54 and therethrough cause the coin-ring 48 connected therewith to swing forwardly from below a coin-tube 20 and carry a coin to an 20 opening 49 in the bottom plate 23, said coin falling through said opening into the hand of the operator. As soon as pressure is released from the thumb-piece 71, the spring 25 60 will restore the key-frame 58 and its connected parts, including the coin-ring, to initial position. I utilize the legs 57 as 30 means for preventing undue forward tilting of the key-frames 58 by causing said legs to engage the rear edge of the openings 35 in the base-plate 21 (Fig. 9). The legs 30 57 perform no duty other than to limit the movements of the tilttable frames 58. All of the frames 58 are alike and all operate similar mechanisms for the respective tubes 20.

35 The side plates 24 have at their rear edges, vertical sleeves 75, 76, 77 (Fig. 17), at their lower edges inwardly curled flanges or beadings 78 and at their front edges inwardly curled beadings or flanges 79, 80 which finish and strengthen said front edges. The sleeves 75, 76, 78 are in line with the sleeves 81 of the base-plate 21 and receive the bolts or rods 63 whose upper ends are headed and engage the top or cover plate 22 and whose 40 lower ends extend through the holes 62 of the bottom plate 23 and receive nuts, as shown in Fig. 7. The bolts or rods 63 thus serve to secure the plates 21, 22, 23 and sides 24 in assembled relation. The flanges 78 on 45 the lower edges of the sides 24 hook under the bottom plate 23 and serve as legs for the device and also as supporting means for the bottom plate 23 and its connected parts. The flanges 80 of the sides 24 extend around 50 the front edges of the vertical flanges 30 on the base-plate 21, as shown in Fig. 10, and thereby the forward edges of said sides 24 are retained in position. The sides 24 lie against the outer faces of the flanges 30 and 55 in this position serve to prevent endwise movement of the pivot rod 40.

60 The back plate or door 25 is a metal plate having a sleeve 81 at one edge through which the bolt 63 at that portion of the device

passes and thereby hinges said plate 25 to 65 the device. The sleeve 81 fits between the facing ends of the sleeves 75, 76 of the adjacent side plate 24, as shown at the right hand side of Fig. 2. At the edge of the back plate or door 25 opposite to the sleeve 81 is 70 a spring snap loop 82 (Figs. 6 and 14) to engage one of the rods 63 and latch the door or plate in closed position.

The back plate or door 25 has at its upper edge a forwardly curled beading 83 which 75 when the plate or door is in closed position extends over the rear edge of the cover-plate 22 (Figs. 1 and 14), and said plate or door 25 has at its lower edge a forwardly curled beading 84 which extends under the rear 80 edge of the bottom plate 23 (Figs. 7 and 14) and serves as a support therefor and also as a leg for the device when the device is placed on a table or other surface. The beading 84 and side flanges 78 cooperate as supporting 85 legs.

The back plate or door 25 is strengthened by being longitudinally corrugated, as at 85.

I equip the device with suitable hooks 86 to be caught upon a belt or the like, and 90 these hooks are shown as swiveled on the sleeves 75 of the side plates 24.

It is believed that the construction and 95 operation of the mechanism constituting my coin-holding and delivering device will be 100 fully understood from the foregoing detailed description. I desire, however, to call attention to several advantages which are accomplished by the structural features of the device. In the first place I call attention to 105 the fact that all the parts of the mechanism are, in the main, produced by dies and hence are accurate and capable of ready assembly, and further it is to be noted that the parts of the device are assembled without the use 110 of solder, rivets or the like, the two bolts or rods 63 serving to secure the parts together after their assembly. The hinged back plate or door 25 when closed conceals the entire back of the device and when opened exposes 115 the mechanism for such attention as it may require. For illustration, if the delivery mechanism for any one tube 20 should require repair or renewal, the spring 60 therefor may be unhooked from the studs 59, 61 and removed, and then the key-frame 58 may be lifted from the rod 40, leaving the pinion 55, with its stem 54, free to be lifted 120 from the base-plate 21 and the ring 48 free to be slid rearwardly out from between the plates 21, 23. Any of the parts thus detached may be repaired or a new part may be substituted for a broken part, and the mechanism may by a reverse order of procedure 125 be restored to operative position. The mechanism has been constructed with the view of enabling the device to withstand rough usage but in the event of impairment of any

of the parts of the device, said parts in accordance with my invention may be readily replaced without disassembling the entire structure and without special skill or the necessity for special tools.

What I claim as my invention and desire to secure by Letters Patent, is:

1. A coin-holding and delivery device comprising a plurality of vertical coin-holding tubes, a cover-plate therefor, a base-plate for said tubes, a bottom plate spaced below said base-plate and having outlets for discharged coins, oscillatory coin rings between said base-plate and bottom plate and manually operative means for actuating said rings to deliver the coins held by them, said base-plate having openings above said rings and below said tubes and vertical flanges around said openings formed with inturned recessed flanges, and said tubes at their lower end portions having two sets of lugs, one set being adapted to be inserted downwardly through said recesses and carried, by turning the tubes, below said flanges and the other set being adapted to rest on top of said flanges.

2. A coin-holding and delivery device comprising a plurality of vertical coin-holding tubes, a cover-plate therefor, a base-plate for said tubes, a bottom plate spaced below said base-plate and having outlets for discharged coins, oscillatory coin rings between said base-plate and bottom plate and manually operative means for actuating said rings to deliver the coins held by them, said base-plate having openings above said rings and below said tubes, and said cover plate having recessed caps for the upper ends of said tubes and a depending front flange bent rearwardly toward said tubes, and said tubes having forwardly projecting lugs extending above the rearwardly bent portion of said front flange.

3. A coin holding and delivery device comprising a plurality of vertical coin-holding tubes, a cover-plate therefor, a base plate for said tubes, a bottom plate spaced below said base-plate and having outlets for discharged coins, oscillatory coin rings between said base-plate and bottom plate and manually operative means for actuating said rings to deliver the coins held by them, said base-plate having openings above said rings and below said tubes, and said rings having shank members pivotally secured at their outer ends and from which said rings receive oscillatory movements, said rings and their shank members varying in thickness to comply with the varying thicknesses of the coins held by said tubes and said shank members having upwardly projecting lugs whose upper ends are on a horizontal plane close to the lower surface of said base plate.

4. A coin-holding and delivery device comprising a plurality of vertical coin-holding

tubes, a cover-plate therefor, a base-plate for said tubes, a bottom plate spaced below said base-plate, coin-delivery devices between said base-plate and said bottom plate, manually operative means above said base-plate for actuating said delivery devices, vertical plates at the sides of the device having inturned flanges at their lower ends extending below said bottom plate, and bolts securing all said plates together at the rear corners of the device, said side plates and said base-plate having aligned sleeves through which said bolts extend and said base-plate being flanged inwardly below said bottom plate to aid in supporting the same.

5. A coin-holding and delivery device comprising a plurality of vertical coin-holding tubes, a cover-plate therefor, a base-plate for said tubes, a bottom plate spaced below said base-plate, coin-delivery devices between said base-plate and said bottom plate, manually operative means above said base-plate for actuating said delivery devices, vertical plates at the sides of the device having inturned flanges at their lower ends extending below said bottom plate, and bolts securing all said plates together at the rear corners of the device, said base-plate having vertical end flanges, said side plates at their forward edges having flanges which hook around said end flanges of the base-plate, and said base-plate being flanged inwardly below said bottom plate to aid in supporting the same.

6. A coin-holding and delivery device comprising a plurality of vertical coin-holding tubes, a cover-plate therefor, a base-plate for said tubes, a bottom plate spaced below said base-plate, coin-delivery devices between said base-plate and said bottom plate, manually operative means above said base-plate for actuating said delivery devices, vertical plates at the sides of the device having inturned flanges at their lower ends extending below said bottom plate, and bolts securing all said plates together at the rear corners of the device, said base-plate having vertical end flanges formed at their rear edges with vertical sleeves, said side plates at their forward edges having flanges which hook around said end flanges of the base-plate and at their rear edges having vertical sleeves above and below and aligned with said sleeves on said end flanges, said base-plate being flanged below said bottom plate to aid in supporting the same, and said bolts being extended through said sleeves.

7. A coin-holding and delivery device comprising a plurality of vertical coin-holding tubes, a cover-plate therefor, a base-plate for said tubes, a bottom plate spaced below said base-plate, coin-delivery devices between said base-plate and said bottom plate, manually operative means above said

- base-plate for actuating said delivery devices, vertical plates at the sides of the device having inturned flanges at their lower ends extending below said bottom plate, 5 bolts securing all said plates together at the rear corners of the device, and a displaceable back-plate flanged forwardly at its upper and lower edges to engage said cover-plate and said bottom plate respectively, said base-plate being flanged below said bottom plate to aid in supporting the same, and said back plate when displaced exposing said operative means for such attention as the same may require.
- 10 8. A coin-holding and delivery device comprising a plurality of vertical coin-holding tubes, a cover-plate therefor, a base-plate for said tubes, a bottom plate spaced below said base-plate, coin-delivery devices 15 between said base-plate and said bottom plate, manually operative means above said base-plate for actuating said delivery devices, vertical plates at the sides of the device having inturned flanges at their lower 20 ends extending below said bottom plate, bolts securing all said plates together at the rear corners of the device, and a back plate hinged at one edge on one of said corner bolts and having at its other edge 25 a snap-catch to engage the other corner bolt, said back plate when opened exposing said operative means for such attention as the same may require.
- 30 9. A coin-holding and delivery device comprising a plurality of vertical coin-holding tubes, a cover-plate therefor, a base-plate for said tubes, a bottom plate spaced below said base-plate, coin-delivery devices 35 between said base-plate and said bottom plate, manually operative means above said base-plate for actuating said delivery devices, vertical plates at the sides of the device having inturned flanges at their lower 40 ends extending below said bottom plate, bolts 45 securing all said plates together at the rear corners of the device, and a back plate hinged at one edge on one of said bolts and at its opposite edge having means to engage the other corner bolt and said back plate 50 having upper and lower flange portions extending forwardly above the cover plate and below the bottom plate respectively, and said base-plate being flanged under said bottom plate.
- 55 10. A coin-holding and delivery device comprising a plurality of vertical coin-holding tubes, a cover-plate therefor, a base-plate for said tubes, a bottom plate spaced 60 below said base-plate, coin-delivery devices 65 between said base-plate and said bottom plate, manually operative means above said base plate for actuating said delivery devices, corner bolts connecting said plates in assembled relation, and a displaceable 70 back plate flanged forwardly at its upper

and lower edges to engage said cover plate and said bottom plate respectively, said base-plate being flanged below said bottom plate to aid in supporting the same, and said back plate when displaced exposing said operative means for such attention as the same may require.

11. A coin-holding and delivery device comprising a plurality of vertical coin-holding tubes, a cover-plate therefor, a base-plate for said tubes, a bottom plate spaced below said base-plate, coin-delivery devices between said base-plate and said bottom plate, manually operative means above said base plate for actuating said delivery devices, corner bolts connecting said plates in assembled relation, and a back-plate hinged at one edge on one of said bolts and having at its opposite edge a snap-catch to engage the other corner bolt, said back plate when opened exposing said operative means.

12. A coin-holding and delivery device comprising a plurality of vertical coin-holding tubes, a cover-plate therefor, a base-plate for said tubes, a bottom plate spaced below said base-plate, coin-delivery devices between said base-plate and said bottom plate, manually operative means above said base plate for actuating said delivery devices, corner bolts connecting said plates in assembled relation, and a back plate hinged at one edge on one of said bolts and at its opposite edge having means to engage the other corner bolt and said back plate having upper and lower flange portions extending forwardly above the cover plate and below the bottom plate respectively, and said base-plate being flanged under said bottom plate.

13. A coin-holding and delivery device comprising a plurality of vertical coin-holding tubes, a base-plate therefor, a bottom plate spaced below said base-plate, oscillatory coin-delivery rings between said plates having actuating arms, and actuating mechanism for said rings comprising, for each ring and tube, a pinion member mounted on said base-plate and having on its upper surface a tooth and at one end a depending stem whose lower end is polygonal and detachably engaged in a polygonal opening in the arm of the ring, a tiltable key-frame detachably mounted over said base-plate and having a forward thumb-piece, a depending slotted member adapted to mesh with said tooth and a depending leg member serving to limit the movement of said frame, and a vertical coiled spring engaged at its upper end with the said frame and at its lower end with a portion of the main structure.

14. A coin-holding and delivery device comprising a plurality of vertical coin-holding tubes, a base-plate therefor, a bottom plate spaced below said base-plate, oscillatory coin-delivery rings between said plates

each ring and tube, a pinion member mounted on said base-plate and having on its upper surface a tooth and at one end a depending stem whose lower end is polygonal and detachably engaged in a polygonal opening in the arm of the ring, a tilttable key-frame detachably mounted over said base-plate and having a forward thumb-piece, a depending slotted member adapted to mesh with said tooth and a depending leg member serving to limit the movement of said frame, and a vertical coiled spring engaged at its upper end with the said frame and at its lower end with a portion 15 of the main structure, the means tiltably mounting the key-frames being standards integral with and bent up from the said base-plate and apertured at their upper ends and a horizontal rod held in the apertures 20 of said standards and the upper ends of slots in the depending members of said frames and seated on said rod, and said frames being adapted to be independently lifted from said rod when released from their springs.

20. A coin-holding and delivery device comprising a plurality of vertical coin-holding tubes, a base-plate therefor, a bottom plate spaced below said base-plate, oscillatory coin-delivery rings between said plates having actuating arms, and actuating mechanism for said rings comprising, for each ring and tube, a pinion member mounted on said base-plate and having 30 on its upper surface a tooth and at one end a depending stem whose lower end is polygonal and detachably engaged in a polygonal opening in the arm of the ring, a tilttable key-frame detachably mounted over said base-plate and having a forward thumb-piece, a depending slotted member adapted 35 to mesh with said tooth and a depending leg member serving to limit the movement of said frame, and a spring under tension holding said frame in initial position for operation and returning the same to such position after each operation.

21. A coin-holding and delivery device comprising a plurality of vertical coin-holding tubes, a base-plate therefor, a bottom plate spaced below said base-plate, oscillatory coin-delivery rings between said plates having actuating arms, and actuating mechanism for said rings comprising, for 50 each ring and tube, a pinion member mounted on said base-plate and having on its upper surface a tooth and at one end a depending stem whose lower end is polygonal and detachably engaged in a 55 polygonal opening in the arm of the ring, a tilttable key-frame detachably mounted over said base-plate and having a forward thumb-piece, a depending slotted member adapted to mesh with said tooth and a 60 depending leg member serving to limit the 65

movement of said frame, and a spring under tension holding said frame in initial position for operation and returning the same to such position after each operation, the means tiltably mounting the key-frames being a horizontal rod sustained in standards and the upper ends of slots in the depending members of said frames and seated on said rod, and said frames being adapted to be independently lifted from said rod when released from their springs.

22. A coin-holding and delivery device comprising a plurality of vertical coin-holding tubes, a base-plate therefor, a bottom plate spaced below said base-plate, oscillatory coin-delivery rings between said plates having actuating arms, and actuating mechanism for said rings comprising, for each ring and tube, a pinion member mounted on said base-plate and having on its upper surface a tooth and at one end a depending stem whose lower end is polygonal and detachably engaged in a polygonal opening in the arm of the ring, a tilttable key-frame detachably mounted over said base-plate and having a forward thumb-piece, a depending slotted member adapted to mesh with said tooth and a depending leg member serving to limit the movement of said frame, and a spring under tension holding said frame in initial position for operation and returning the same to such position after each operation, the means tiltably mounting the key-frames being standards integral with and bent up from the said base-plate and apertured at their upper ends and a horizontal rod held in the apertures of said standards and the upper ends of slots in the depending members of said frames and seated on said rod, and said frames being adapted to be independently lifted from said rod when released from their springs.

23. A coin-holding and delivery device comprising a plurality of vertical coin-holding tubes, a base plate therefor, a bottom plate spaced below said base plate, oscillatory coin delivery rings between said plates having actuating arms, and actuating mechanism for said rings comprising, for each ring and tube, a pinion member mounted on said base-plate and having on its upper surface a tooth and at one end a depending stem whose lower end is polygonal and detachably engaged in a polygonal opening in the arm of the ring, a tilttable key-frame mounted over said base-plate and having a forward thumb-piece, a depending slotted member adapted to mesh with said tooth and a stop member to limit the movement of said frame, and a vertical coiled spring engaged at its upper end with said frame and at its lower end with a portion of the main structure.

24. A coin-holding and delivery device

comprising a plurality of vertical coin-holding tubes, a base plate therefor, a bottom plate spaced below said base-plate, oscillatory coin delivery rings between said plates having actuating arms and actuating mechanism for said rings comprising, for each ring and tube, a pinion member mounted on said base-plate and having on its upper surface a tooth and at one end 5 a depending stem whose lower end is polygonal and detachably engaged in a polygonal opening in the arm of the ring, 10 a tiltable key-frame mounted over said base plate and having a forward thumb-piece, a depending slotted member adapted to mesh with said tooth and a stop member to limit the movement of said frame, and a spring under tension holding said frame in initial position for operation and returning the same to such position after 15 each operation. 20

Signed at New York city, in the county of New York and State of New York, this 28th day of June, A. D. 1922.

SEYED KHALIL.
